[57] CLAIM

The ornamental design for a simulative toy typewriter, as shown and described.

DESCRIPTION

FIG. 1 is a perspective view of a simulative toy typewriter showing my new design;

FIG. 2 is a left side elevational view thereof;

FIG. 3 is a right side elevational view thereof; and

FIG. 4 is a rear elevational view thereof.

The bottom of the claimed design is substantially flat, plain and un-ornamented.
